UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed June 17, 1921. Serial No. 478,396. Renewed March 26, 1925.

My invention relates to mining machines.

It has for its object to provide an improved mining machine. A further object of my invention is to provide a mining machine having improved feeding mechanism adapted to exert the desired variable speed feeding action and to be manufactured at materially reduced expense. A still further object of my invention is to provide a mining machine having an improved variable speed truck drive preferably driven and controlled by the feeding mechanism. These and other objects of my invention will, however, hereinafter more fully appear.

In the accompanying drawings I have shown for purposes of illustration one embodiment which my invention may assume in practice.

In these drawings,—

Fig. 1 is a side elevation of a machine equipped with my improvement and mounted on its transport truck.

Fig. 2 is a side elevation on the opposite side of the machine when the latter is removed from the truck and in cutting position on the bottom.

Fig. 3 is a side elevation partially in section of the rear end of the machine shown in Fig. 2.

Fig. 4 is a sectional view on line 4—4 of Fig. 3.

Fig. 5 is a sectional view on line 5—5 of Fig. 3.

Fig. 6 is a sectional view on line 6—6 of Fig. 3.

Fig. 7 is a detail sectional view on line 7—7 of Fig. 6.

In this illustrative construction I have shown a machine of the general reversible type described and claimed in my co-pending application Ser. No. 232,803, filed May 6, 1918 and comprising a machine frame 1 carrying a usual cutter bar 2, having a cutter chain 3 thereon driven by mechanism hereinafter described, and a feed operating member 4 disposed on a transverse axis and cooperating with a flexible feeding member 5 disposable relative to idlers 6, 7, 8, and 9 on the machine to propel the machine on the mine bottom; a truck driving member 10, also on a transverse axis, being provided on the opposite side of the machine and connected through a sprocket and chain connection 11 to the wheels 12 of a truck 13 to propel the machine about the mine when

the same is mounted upon the truck; and the feed operating and truck driving members 4 and 10 being transposable at will with the necessary idlers in such a manner as to enable the machine to be used as either a right or left hand cutter.

In my improved construction, the horizontal armature shaft 14 of the machine motor 15 carries on its rear end a bevel pinion 16 meshing with a larger bevel gear 17 keyed as at 18 to an upright shaft 19 supported on the frame in suitable roller bearings 20 and an upper adjustable bearing 21 removable through the top of the frame. This shaft 19 has fixed to its lower end a helical gear 22 which in turn meshes with a larger helical gear 23 fixed as by one or more screws 24 to a cutter chain sprocket journal 25 which is in turn keyed as at 26 to another rearwardly located upright shaft 27 suitably journaled at its upper end in the frame as hereinafter described and having a collar 28 upon its lower end. This collar, as shown, rests upon a bearing ring 29 which is in turn supported on a bearing sleeve 30 rotatable on suitable roller bearings 31 housed in a removable shoe plate 32 having its outer surface lying flush with the shoe 33 of the machine and attached to the frame of the machine by suitable screws 34. As shown a ring-like member 35 is attached as by screws 36 to the member 25 and a cooperating sleeve 37 is provided between the member 25 and a cutter chain sprocket 38 which is rotatable thereon and adapted to be connected to the gear 23 by any usual form of cutter chain clutch fingers 39 movable through apertures 40 in the gear 23 and into engagement with suitable teeth 41 formed on the upper end of the sprocket sleeve. As this last is a well known construction common in mining machines, the same is not illustrated in detail herein, it being sufficient to say that a plurality of the members 39 is provided on a clutch spider 42 adjustable on the shaft 27 toward and from clutching position by a shipper yoke 43 pivoted at 44 on a transverse pivot on the frame and operable through an eccentric, detent controlled, operating lever 45 on the side of the machine.

Operatively connected to the cutter chain driving mechanism is improved feeding mechanism. As shown a worm 46 is keyed as at 47 to the shaft 27 at a point above

the clutch yoke 43 and meshes with a worm gear 48 rotatably mounted on a transverse driving shaft 49 suitably journaled as hereinafter described on the frame and carrying at its opposite ends the feed operating member 4 and truck driving member 10. As shown the upper end of the shaft 27 is suitably journaled in roller bearings 50 carried on an upper removable frame member, and the upper end of this shaft has adjustably fixed thereto, as by a screw 52 and a key 53, a pinion 54 meshing with a larger gear, herein in a sectional gear 55, similarly attached as by a screw 56 and a key 57 to the upper end of another upright but shorter shaft 58 journaled in bearings 59 and 60 on the frame and carrying between its ends a worm 61 of considerably less pitch than the worm 46. This worm 61 in turn meshes with a worm gear 62 rotatably mounted on the shaft 49, both the worm gears 48 and 62 being carried on clutch sleeves 63 and 64, respectively, having teeth 65 and 66 adapted to be engaged by corresponding teeth 67 and 68 on movable clutch sleeves 69 and 70 movable longitudinally of the shaft to connect the members 63 and 64 to or disconnect the same from correspondingly toothed sleeves 63' and 64' fixed to a sleeve 71 surrounding the shaft 49 and connectable thereto at will through friction clutch mechanism adjacent the feed operating member 4. As shown the sleeve 71 is provided with a flange 72 suitably connected as by screws 73 to the rotatable member 74 on the friction clutch 75 surrounding the shaft, the other member 76 of the clutch being keyed to the shaft as at 77 and the pressure exerted on the clutch being controlled by an annular movable cylinder 78 movable relative to a corresponding stationary annular piston 79 to which suitable fluid or liquid pressure is supplied through a conduit 80 from a hand operated pump 81. As shown, the feed operating member 4 is keyed as at 82 to the adjacent end of the shaft 49 and held in position thereon by a screw and washer 83, the feed operating member also being provided with a sleeve 84 suitably rotatably mounted in ball bearings 85 disposed between the sleeve and a stationary piston carrying member 86 suitably fixed to the frame and having the conduit 80 therein.

Attention is also directed to the fact that the gear 23 also meshes with a helical pinion 87 on the lower end of a second short upright shaft 88 suitably journaled above the pinion on the frame in suitable roller bearings 89 and at its upper end in suitable ball bearings 90 surrounding a positioning sleeve 91 keyed to the shaft at 92 and adjusted thereon by an adjusting screw 93, the ball bearings being held in position by a suitable clamping member 94 and being seated in a removable flanged sleeve 95 so that the bearings and shaft may be removed bodily through the

top of the frame. Keyed upon this shaft 88 is a third worm 96 of the same pitch as the worm 46, and this worm, as shown, meshes with a worm gear 97 which is in turn carried on a clutch sleeve 98, similar to the sleeves 63 and 64 and similarly rotatable on the sleeve 71, and provided with teeth 99 connectable by the clutch member 69, the clutch member 69 thus serving to connect either the worm 97 or the worm 48 to the sleeve 71, while the clutch member 70 serves to connect the worm 62 to that sleeve.

Operatively connected to the clutch members 69 and 70 as by fork members 100 are control sleeves 101 and 102 carried on a reciprocable rod 103 supported on the opposite sides of the frame and movable about its axis and transversely relative to the frame by a control handle 104. As shown, the sleeve 101 is provided with an L-shaped slot 105 which in turn receives a pin 106 fixed to the rod 103 and movable with the rod as the latter rotates about its axis or moves longitudinally when the parts are in the position shown in Fig. 7, the rod thus being movable independently of the clutch member when the rod is turned downward from the position shown and the pin then moving in one direction in the long arm of the L-shaped slot without exercising any control over the clutch member to cause it to connect the members 67 and 63, while in any position a movement of the rod in a reverse longitudinal direction will cause the member 69 to connect the members 67 and 99. The sleeve 102 is similar to the sleeve 101 but provided with a T-shaped slot 107 so that the rod may be moved longitudinally in opposite directions relative to the sleeve and only operate the clutch member 70 when it is in the short base of the T slot. In order that the sleeves may be held in any desired position of adjustment, the surface of each of the same is notched in two places as at 109 to receive a ball 110 held in place by a spring 111 acting between the ball and a threaded holding sleeve 112 carried by the frame, and a supplemental notch 113 being provided on the sleeve 101.

In the operation of my improved construction it will be evident that the connection of all the worms 48, 62 and 97 will be controlled by the friction clutch 75 and that any one of the worm wheels may be connected to the sleeve 71 by suitable manipulation of the clutch members 69 and 70 to produce feeds of varying speed and in reverse directions, for example, a slow or cutting speed may be obtained through the use of the worm 61, whereas by use of the worm 46 a reverse fast speed may be obtained, while by use of the worm 96 a still faster truck driving speed may be obtained. Attention is also directed to the fact that through the friction 75 not only may the

- parts be connected but the speed may be varied as desired, and to the further fact that through the control member 104, the different speeds may be very easily obtained, 5 the member 104 being held in each position against accidental operation by the balls 110 and through its controlling sleeves rendered incapable of connecting two feeds simultaneously.
- 10 Here attention is also directed to the fact that the truck driving sprocket 10 is herein removably mounted on the shaft 49, the same being adapted to be connected to or disconnected therefrom through a threaded member 114 and a sleeve 115 receiving the sprocket, the two members 10 and 115 having clutch mechanism 116 between the same so that when the member 114 is released the member 10 may be withdrawn from engagement with the teeth 116 and permit the shaft 49 to rotate independently thereof, whereas, when the member 112 is connected, the sprocket 10 will rotate with the shaft. Here attention is also directed to the fact 25 that a ball bearing 117 is disposed between the sleeve 115 and a suitable collar 118 on the shaft, and that the sleeve and sprocket may accordingly be removed and transposed with the feed operating member 4 whenever desired. The feature of the clutch connection for the sprocket 10 and the transposable sprocket and feed operating member does not, however, enter into the present invention, the same being described 30 and claimed in my co-pending application mentioned above, and it is accordingly unnecessary for them to be described more in detail than to say that since the member 10 is thus connected to the shaft it may be driven at varying speeds through the feeding mechanism as described whenever desired or disconnected entirely from the shaft.
- 45 As a result of my improved construction it will be noted that the feed and truck driving mechanism is compactly disposed at the rear of the machine and that the construction is such that the desired variations in speed of feed or truck drive may be obtained through an exceedingly simple mechanism of rugged type which may be manufactured at small expense and which is at the same time exceedingly accessible, the member 86 or its counterpart on the opposite side of the frame being removable when desired to permit the mechanism associated with the shaft 49 to be withdrawn laterally whenever desired, while the removable cover on the frame permits of the desired access to the worms and the cutter chain driving gearing.
- 55 While I have in this application specifically described one form which my invention may assume in practice, it will be understood that this form has been shown for purposes of illustration and that the invention may be otherwise embodied and practiced without departing from its spirit or the scope of the appended claims.
- 60 What I claim as new and desire to secure by Letters Patent is:—
1. In a mining machine, a feed operating shaft, a plurality of driving worms rotating on axes perpendicular to a plane in which the axis of said shaft lies, a plurality of worm gears on said shaft, a sleeve between said worm gears and shaft and connectible to said shaft, means for alternatively connecting and disconnecting said sleeve and shaft, and means for selectively connecting 75 said gears to said sleeve.
  2. In a mining machine, a feed operating shaft, a plurality of worms of different pitch rotating on axes perpendicular thereto, a plurality of cooperating worm gears on said shaft, a sleeve between said worm gears and shaft, a clutch controlling the connection of said sleeve to said shaft, and means for selectively connecting said worm gears to said sleeve.
  3. In a mining machine, a feed operating shaft, a plurality of driving members therefor concentric therewith, a sleeve on said shaft, friction clutch means for connecting said sleeve to said shaft and disconnecting it therefrom, and means for selectively connecting said driving members to said sleeve.
  4. In a mining machine, a feed operating shaft, a plurality of driving members concentric therewith and spaced apart thereon, a sleeve on said shaft, friction clutch means for connecting said sleeve to said shaft or disconnecting it therefrom, means for selectively connecting said driving members to said sleeve, and a feed operating member driven by said shaft and coaxial therewith.
  5. In a mining machine, a feed operating shaft, a plurality of drive members concentric therewith and spaced apart thereon, a sleeve on said shaft, friction clutch means for connecting said sleeve to said shaft or disconnecting it therefrom, means for selectively connecting said driving members to said sleeve, and a truck driving member driven by said shaft.
  6. In a mining machine, a feed operating shaft, a plurality of driving members concentric therewith and spaced apart thereon, a sleeve on said shaft, friction clutch means for connecting said sleeve to said shaft or disconnecting it therefrom, means for selectively connecting said driving members to said sleeve, and feed operating and truck driving members driven by said shaft.
  7. In a mining machine, a feed operating shaft, a plurality of driving members concentric therewith and spaced apart thereon, a sleeve on said shaft, friction clutch means for connecting said sleeve to said

- 4
- shaft or disconnecting it therefrom, means for selectively connecting said driving members to said sleeve, and feed operating and truck driving members carried on the opposite ends of said shaft.
8. In a mining machine, a feed operating shaft, a plurality of driving elements therefor spaced apart thereon, a plurality of means for connecting said driving elements thereto, a friction clutch controlling the connection of each of said means to said shaft, and a single means for selectively operating said plurality of connecting means.
9. In a mining machine, a feed operating shaft, a plurality of driving elements therefor spaced apart thereon, a plurality of means for connecting said driving elements thereto, a friction clutch controlling the connection of each of said means to said shaft, and a single means for selectively operating said plurality of connecting means including a controlling member disposed parallel to said shaft.
10. In a mining machine, a cutter chain sprocket rotating element, a worm shaft coaxial therewith and rotatable therewith, a plurality of parallel worm shafts, and driving connections between one end of one of the same and said worm shaft and between the opposite end of the other of the same and said cutter chain sprocket rotating element, a feed operating member, and driving connections between said worms and said member.
11. In a mining machine, a cutter chain sprocket rotating element, a worm shaft coaxial therewith and rotatable therewith, a plurality of parallel worm shafts, and driving connections between one end of one of the same and said worm shaft and between the opposite end of the other of the same and said cutter chain sprocket rotating element, a feed operating member, and driving connections between said worms and said member including a plurality of selectively operable clutches.
12. A mining machine slidable on a mine bottom comprising flexible lateral feeding mechanism including a transverse feed operating shaft, a feed operating member adapted to cooperate directly with a flexible feeding member and driven by said shaft and rotatable on an axis parallel to a line parallel to said shaft, a plurality of worm gears on said feed operating shaft and selectively connectible therewith, a plurality of worms meshing therewith, and means for rotating said worms in different directions.
13. A mining machine slidable on a mine bottom comprising flexible lateral feeding mechanism including a transverse feed operating shaft, a feed operating member adapted to cooperate directly with a flexible feeding member and mounted on and driven by said shaft, a plurality of worm gears on said feed operating shaft and selectively connectible therewith, a plurality of worms meshing therewith, and means for rotating said worms in different directions.
14. In a mining machine of the character which performs its normal cutting operations while sliding upon the mine bottom and is transported from one working place to another upon a truck from which it is dismounted during the normal cutting operations aforesaid, a machine frame slidable on the mine bottom during cutting, a transverse feed operating shaft, a feed operating member driven thereby, a plurality of worm gears on said feed operating shaft and selectively connectible therewith, and means including a plurality of worms for rotating certain of said worm gears in the same direction at different predetermined speeds and one of said gears in an opposite direction at a slower predetermined speed than one of said first mentioned speeds.
15. A mining machine slidable on a mine bottom comprising flexible lateral feeding mechanism including a laterally extending feed operating member, motor driven cutting mechanism, and a plurality of worm trains driven by said cutting mechanism for selectively driving said feed operating member.
16. A mining machine slidable on a mine bottom comprising flexible lateral feeding mechanism including a laterally extending feed operating member, motor driven cutting mechanism including a cutter chain sprocket, and a plurality of worm trains for selectively rotating said feed operating member including a worm rotatable with said sprocket and a second worm rotatable by said first mentioned worm.
17. A mining machine slidable on a mine bottom during normal cutting operations and comprising flexible lateral feeding mechanism including a laterally extending feed operating member, motor driven cutting mechanism including helical gearing and a cutter chain sprocket driven thereby, and a plurality of worm trains rotatable with said sprocket for selectively rotating said feed operating member.
18. A mining machine slidable on a mine bottom during normal cutting operations and comprising flexible feeding mechanism including a laterally extending feed operating member, truck driving mechanism including a laterally extending truck driving member, a plurality of worm gear trains for selectively driving said feed operating member, and a cooperating train for driving said truck driving member.
19. A mining machine slidable on a mine bottom during normal cutting operations and comprising flexible feeding mechanism including a laterally extending feed operat-

ing member, truck driving mechanism including a laterally extending truck driving member, a plurality of worm gear trains for selectively driving said feed operating member, and a cooperating worm gear train for driving said truck driving member, said worm gear trains each including an upright worm.

20. A mining machine slideable on a mine bottom during normal cutting operations and comprising flexible feeding mechanism including a laterally extending feed operating member, truck driving mechanism including a laterally extending truck driving member, a plurality of worm gear trains for selectively driving said feed operating member, and a cooperating worm gear train for driving said truck driving member, said worm gear trains each including an upright worm.

21. A mining machine comprising a machine frame slideable on the mine bottom during cutting and flexible feeding mechanism including a laterally extending feed operating member and flexible feeding means cooperating directly therewith to effect lateral feeding, cutting mechanism including a horizontally disposed cutter chain driving sprocket, and means for driving said feed operating member at different speeds including an upright worm rotatable with said sprocket and a second worm geared to said first mentioned worm and of different pitch therefrom.

35 22. In a mining machine, a machine frame slideable upon the mine bottom during normal cutting operations and feed operating mechanism therefor including a feed operating member, driving mechanism for selectively driving said member including a plurality of rotating members and a common member to which said rotating members are severally connectible, and means for selectively connecting said rotating members directly to said common member including clutches on opposite sides of one of said rotating members.

23. In a mining machine, feed operating mechanism including a feed operating member, driving mechanism for selectively driving said member including a plurality of rotating members and a common shaft, and means for selectively connecting said rotating members to said shaft including clutches on opposite sides of one of said rotating members and a friction clutch between each of said rotating members and said shaft.

24. In a mining machine, feed operating and truck driving mechanism including a feed operating member and a truck driving member, driving mechanism for selectively driving said members including a plurality of rotating members and a common shaft, and means for selectively connecting said rotating members to said shaft including

clutches on opposite sides of one of said rotating members, a friction clutch between each of said rotating members and said shaft, and a clutch between said truck driving member and said shaft.

25. In a mining machine, feed operating mechanism including a feed operating member, driving mechanism for selectively driving said member including a plurality of rotating members and a common shaft, and means for selectively connecting said rotating members to said shaft including clutches on opposite sides of one of said rotating members, a plurality of clutch shipping members, and a single control member having connections for operating either of said shipping members while the other remains stationary.

26. In a mining machine, feed operating and truck driving mechanism including a feed operating member and a truck driving member, driving mechanism for selectively driving said members including a plurality of rotating members and a common shaft, and means for selectively connecting said rotating members to said shaft including clutches on opposite sides of one of said rotating members and a plurality of clutch shipping members having a common control member and selectively movable thereby.

27. Mining machine mechanism including a plurality of rotating members, a shaft on which said members are carried, clutches for said members on opposite sides of one of said members operative to connect the latter to said shaft, and means for selectively operating either of said clutches while the other remains stationary having a single operating handle.

28. A room and pillar mining machine including a motor having its armature shaft rotatable on an axis extending longitudinally of the machine, a bevel driving pinion upon the rear end of said shaft, a vertical shaft arranged to the rear of said armature shaft and carrying a bevel gear adjacent the upper end thereof meshing with said driving pinion, a driving connection between said vertical shaft and said cutter chain driving sprocket, and means driven by said motor for feeding and guiding said machine bodily towards and laterally along a mine face during cutting including horizontally journaled feed operating means adapted to cooperate directly with flexible feeding means, and actuating means for said feed operating means including a plurality of worms rotatable upon vertical axes.

29. A room and pillar mining machine including a motor having its armature shaft rotatable on an axis extending longitudinally of the machine, a bevel driving pinion upon the rear end of said shaft, a vertical shaft arranged to the rear of said armature shaft and carrying a bevel gear adjacent the upper

end thereof meshing with said driving pinion, a driving connection between said vertical shaft and said cutter chain driving sprocket, and means driven by said motor for feeding and guiding said machine bodily towards and laterally along a mine face during cutting including a feed operating member rotating upon a transversely extending axis, and actuating means therefor including a plurality of worms rotatable upon vertical axes, and means for rendering said worms alternatively operative as driving members.

30. A room and pillar mining machine including a motor having its armature shaft rotatable on an axis extending longitudinally of the machine, a bevel driving pinion upon the rear end of said shaft, a vertical shaft arranged to the rear of said armature shaft 15 and carrying a bevel gear adjacent the upper end thereof meshing with said driving pinion, a driving connection between said vertical shaft and said cutter chain driving sprocket, flexible machine guiding and feeding means providing a plurality of flexible feeding portions extending oppositely from opposite ends of said machine frame during transverse cutting, horizontally journaled feed operating means cooperating with said 20 flexible feeding means, and actuating means for said feed operating means including a transversely extending driving shaft for the latter and actuating means for said shaft including a plurality of worms rotatable upon vertical axes.

31. A room and pillar mining machine including a motor having its armature shaft rotatable on an axis extending longitudinally of the machine, a bevel driving pinion upon 40 the rear end of said shaft, a vertical shaft arranged to the rear of said armature shaft and carrying a bevel gear adjacent the upper end thereof meshing with said driving pinion, a driving connection between said vertical shaft and said cutter chain driving sprocket, flexible machine feeding and guiding means providing a plurality of flexible feeding portions extending oppositely from opposite ends of said machine frame during 45 transverse cutting, horizontally journaled feed operating means cooperating with said flexible feeding means, and actuating means for said feed operating means including a transversely extending driving shaft for the latter and actuating means for said shaft including a plurality of worms one of which is rotatable upon a vertical axis and which are selectively operative as driving members.

32. A room and pillar mining machine including a motor having its armature shaft rotatable on an axis extending longitudinally of the machine, a driving pinion upon the rear end of said shaft, a driving gear meshing with said driving pinion and driven thereby, a shaft upon which said driving

gear is mounted, a driving pinion upon said last mentioned shaft, a driving gear rotatable upon a vertical axis and meshing with said second mentioned driving pinion, a cutter chain driving sprocket, a driving connection between said vertical shaft and said driving sprocket, and means driven by said motor for feeding said machine bodily laterally along a mine face and guiding the same during cutting including horizontally journaled feed operating means, flexible feeding means adapted to cooperate directly with said feed operating means and including portions adapted to be extended in opposite directions from the opposite ends of said machine frame during feeding across the face, and driving means for said feed operating means including a plurality of worms rotatable upon vertical axes.

33. A room and pillar mining machine including a motor having its armature shaft rotatable on an axis extending longitudinally of the machine, a driving pinion upon the rear end of said shaft, a driving gear meshing with said driving pinion and driven thereby, a shaft upon which said driving gear is mounted, a driving pinion upon said last mentioned shaft, a driving gear rotatable upon a vertical axis and meshing with said second mentioned driving pinion, a cutter chain driving sprocket coaxial with said last mentioned gear, a driving connection between said vertical shaft and said driving sprocket, and means driven by said motor for feeding said machine bodily laterally along a mine face and guiding the same during cutting including horizontally journaled feed operating means, flexible feeding means adapted to cooperate directly with said feed operating means and including portions adapted to be extended in opposite directions from the opposite ends of said machine frame during feeding across the face, and driving means for said feed operating means including a plurality of worms rotatable upon vertical axes.

34. A room and pillar mining machine including a motor having its armature shaft rotatable on an axis extending longitudinally of the machine, a driving pinion upon the rear end of said shaft, a driving gear meshing with said driving pinion and driven thereby, a shaft upon which said driving gear is mounted, a driving pinion upon said last mentioned shaft, a driving gear rotatable upon a vertical axis and meshing with said second mentioned driving pinion, a cutter chain driving sprocket, a driving connection between said second mentioned driving gear and said driving sprocket, and means driven by said motor for feeding said machine bodily laterally along a mine face during cutting including feed operating means, flexible feeding means adapted to cooperate directly with said feed operating means and

- including portions adapted to be extended in opposite directions from the opposite ends of said machine frame during feeding across the face, and driving means for said feed 5 operating means including a plurality of worms rotatable upon vertical axes one of which is in alinement with the axis of rotation of said cutter chain driving sprocket.
35. A room and pillar mining machine including a motor having its armature shaft rotatable on an axis extending longitudinally of the machine, a driving pinion upon the rear end of said shaft, a driving gear meshing with said driving pinion and driven 10 thereby, a shaft upon which said driving gear is mounted, a driving pinion upon said last mentioned shaft, a driving gear rotatable upon a vertical axis and meshing with said second mentioned driving pinion, a 15 cutter chain driving sprocket coaxial with said last mentioned gear, a driving connection between said last mentioned gear and said driving sprocket, and means driven by said motor for feeding said machine bodily laterally along a mine face during cutting including 20 feed operating means, flexible feeding means adapted to cooperate directly with said feed operating means and including portions adapted to be extended in opposite directions 25 from the opposite ends of said machine frame during feeding across the face, and driving means for said feed operating means including a plurality of worms rotatable upon vertical axes one of which is in alinement 30 with the axis of rotation of said cutter chain driving sprocket.
36. A room and pillar mining machine including a motor having its armature shaft rotatable on an axis extending longitudinally of the machine, a bevel driving pinion upon the rear end of said shaft, a vertical shaft arranged to the rear of said armature shaft and carrying a bevel gear adjacent the upper 40 end thereof meshing with said driving pinion, a cutter chain driving sprocket a driving connection between said vertical shaft and said cutter chain driving sprocket, and means driven by said motor for feeding and guiding said machine bodily towards and laterally along a mine face during cutting including 45 horizontally journalled feed operating means adapted to cooperate directly with flexible feeding means, actuating means for said operating means including a plurality of worms rotatable upon vertical axes, and friction clutch means between said worms and said feed operating means.
37. A room and pillar mining machine including a motor having its armature shaft 50 rotatable on an axis extending longitudinally of the machine, a bevel driving pinion upon the rear end of said shaft, a vertical shaft arranged to the rear of said armature shaft and carrying a bevel gear adjacent the up- 55 per end thereof meshing with said driving pinion, a cutter chain driving sprocket, a driving connection between said vertical shaft and said cutter chain driving sprocket, and means driven by said motor for feeding and guiding said machine bodily towards and laterally along a mine face during cutting including a feed operating member rotating upon a transversely extending axis, and actuating means therefor including a plurality of worms rotatable upon vertical 60 axes, and means for rendering said worms alternatively operative as driving members including friction clutch means between said worms and said feed operating means.
38. A room and pillar mining machine including a motor having its armature shaft rotatable on an axis extending longitudinally of the machine, a bevel driving pinion upon the rear end of said shaft, a vertical shaft arranged to the rear of said armature shaft 65 and carrying a bevel gear adjacent the upper end thereof meshing with said driving pinion, a cutter chain driving sprocket, a driving connection between said vertical shaft and said cutter chain driving sprocket, flexible machine guiding and feeding means providing a plurality of flexible feeding portions extending oppositely from opposite ends of said machine frame during transverse cutting, horizontally journalled feed 70 operating means cooperating with said flexible feeding means, and actuating means for said feed operating means including a transversely extending driving shaft for the latter and actuating means for said shaft including a plurality of worms rotatable upon vertical axes, and friction clutch means between said worms and said feed operating means.
39. A room and pillar mining machine including a motor having its armature shaft rotatable on an axis extending longitudinally of the machine, a bevel driving pinion upon the rear end of said shaft, a vertical shaft arranged to the rear of said armature shaft 75 and carrying a bevel gear adjacent the upper end thereof meshing with said driving pinion, a cutter chain driving sprocket, a driving connection between said vertical shaft and said cutter chain driving sprocket, flexible machine feeding and guiding means providing a plurality of flexible feeding portions extending oppositely from opposite ends of said machine frame during transverse cutting, horizontally journalled feed 80 operating means cooperating with said flexible feeding means, and actuating means for said feed operating means including a transversely extending driving shaft for the latter and actuating means for said shaft including a plurality of worms rotatable upon vertical axes one of which is rotatable upon a vertical axis and which are selectively operative as driving members.

and also including friction clutch means between said worms and said feed operating means.

40. A room and pillar mining machine including a motor having its armature shaft rotatable on an axis extending longitudinally of the machine, a driving pinion upon the rear end of said shaft, a driving gear meshing with said driving pinion and driven thereby, a shaft upon which said driving gear is mounted, a driving pinion upon said last mentioned shaft, a driving gear rotatable upon a vertical axis and meshing with said second mentioned driving pinion, a cutter chain driving sprocket, a driving connection between said last mentioned driving gear and said driving sprocket, and means driven by said motor for feeding said machine bodily laterally along a mine face during cutting including feed operating means, flexible feeding means adapted to cooperate directly with said feed operating means and including portions adapted to be extended in opposite directions from the opposite ends of said machine frame during feeding across the face, driving means for said feed operating means including a plurality of worms rotatable upon vertical axes, and controlling means including friction clutch means between said worms and said feed operating means.

41. A room and pillar mining machine including a motor having its armature shaft rotatable on an axis extending longitudinally of the machine, a driving pinion upon the rear end of said shaft, a driving gear meshing with said driving pinion and driven thereby, a shaft upon which said driving gear is mounted, a driving pinion upon said last mentioned shaft, a driving gear rotatable upon a vertical axis and meshing with said second mentioned driving pinion, a cutter chain driving sprocket coaxial with said last mentioned gear, a driving connection between said last mentioned gear and said driving sprocket, and means driven by said motor for feeding said machine bodily laterally along a mine face during cutting including feed operating means, flexible feeding means adapted to cooperate directly with said feed operating means and including portions adapted to be extended in opposite directions from the opposite ends of said machine frame during feeding across the face, driving means for said feed operating means including a plurality of worms rotatable upon vertical axes, and controlling means including friction clutch means between said worms and said feed operating means.

42. A room and pillar mining machine including a motor having its armature shaft

rotatable on an axis extending longitudinally of the machine, a driving pinion upon the rear end of said shaft, a driving gear meshing with said driving pinion and driven thereby, a shaft upon which said driving gear is mounted, a driving pinion upon said last mentioned shaft, a driving gear rotatable upon a vertical axis and meshing with said second mentioned driving pinion, a cutter chain driving sprocket, a driving connection between said second mentioned driving gear and said driving sprocket, and means driven by said motor for feeding said machine bodily laterally along a mine face during cutting including feed operating means, flexible feeding means adapted to cooperate directly with said feed operating means and including portions adapted to be extended in opposite directions from the opposite ends of said machine frame during feeding across the face, and driving means for said feed operating means including a plurality of worms rotatable upon vertical axes one of which is in alignment with the axis of rotation of said cutter chain driving sprocket, said driving means including friction clutch means between said feed operating means and said worms.

43. A room and pillar mining machine including a motor having its armature shaft rotatable on an axis extending longitudinally of the machine, a driving pinion upon the rear end of said shaft, a driving gear meshing with said driving pinion and driven thereby, a shaft upon which said driving gear is mounted, a driving pinion upon said last mentioned shaft, a driving gear rotatable upon a vertical axis and meshing with said second mentioned driving pinion, a cutter chain driving sprocket coaxial with said last mentioned gear, a driving connection between said last mentioned driving gear and said driving sprocket, and means driven by said motor for feeding said machine bodily laterally along a mine face during cutting including feed operating means, flexible feeding means adapted to cooperate directly with said feed operating means and including portions adapted to be extended in opposite directions from the opposite ends of said machine frame during feeding across the face, and driving means for said feed operating means including a plurality of worms rotatable upon vertical axes one of which is in alignment with the axis of rotation of said cutter chain driving sprocket, said driving means including friction clutch means between said feed operating means and said worms.

44. A room and pillar mining machine including a motor having its armature shaft rotatable on an axis extending longitudinally of the machine, a cutter chain driving sprocket rotatable upon a vertical axis, driving means therefor including a gear rotat-

- able coaxially therewith, driving connections between said gear and said armature shaft, and means driven by said motor for feeding and guiding said machine bodily towards and laterally along a mine face during cutting including horizontally journaled feed operating means, and actuating means therefor including a plurality of worms rotatable on vertical axes which extended pass within the circumference of a circle coinciding with the periphery of said gear.
45. A room and pillar mining machine including a motor having its armature shaft rotatable on an axis extending longitudinally of the machine, a cutter chain driving sprocket rotatable upon a vertical axis, driving means therefor including a gear rotatable coaxially therewith, driving connections between said gear and said armature shaft, and means driven by said motor for feeding and guiding said machine bodily towards and laterally along a mine face during cutting including horizontally journaled feed operating means, and actuating means therefor including a plurality of worms rotatable on vertical axes which extended pass within the circumference of a circle coinciding with the periphery of said gear, said worms being disposed above said gear.
- 30 46. A room and pillar mining machine including a motor having its armature shaft rotatable on an axis extending longitudinally of the machine, a cutter chain driving sprocket rotatable upon a vertical axis, driving means therefor including a gear rotatable coaxially therewith, driving connections between said gear and said armature shaft, and means driven by said motor for feeding and guiding said machine bodily towards and laterally along a mine face during cutting including horizontally journaled feed operating means, and actuating means therefor including a plurality of worms, one of said worms being coaxial with said gear.
- 45 47. A room and pillar mining machine including a motor having its armature shaft rotatable on an axis extending longitudinally of the machine, a cutter chain driving sprocket rotatable upon a vertical axis, driving means therefor including a gear rotatable coaxially therewith, driving connections between said gear and said armature shaft, and means driven by said motor for feeding and guiding said machine bodily towards and laterally along a mine face during cutting including horizontally journaled feed operating means, and actuating means therefor including a plurality of worms, one of said worms being coaxial with said gear, and friction clutch means between said worms and said feed operating means.
- 50 48. A room and pillar mining machine including a motor having its armature shaft rotatable on an axis extending longitudinally of the machine, a cutter chain driving sprocket rotatable upon a vertical axis, driving means therefor including a gear rotatable coaxially therewith, driving connections between said gear and said armature shaft, and means driven by said motor for feeding and guiding said machine bodily towards and laterally along a mine face during cutting including horizontally journaled feed operating means, and actuating means therefor including a plurality of worms, one of said worms being coaxial with said gear, and friction clutch means between said worms and said feed operating means.
- 55 49. A room and pillar mining machine including a motor having its armature shaft rotatable on an axis extending longitudinally of the machine, a cutter chain driving sprocket rotatable upon a vertical axis, driving means therefor including a gear rotatable coaxially therewith, driving connections between said gear and said armature shaft, and means driven by said motor for feeding and guiding said machine bodily towards and laterally along a mine face during cutting including horizontally journaled feed operating means, and actuating means therefor including a plurality of worms rotatable on vertical axes which extended pass within the circumference of a circle constituting the periphery of said gear, and friction clutch means between said worms and said feed operating means.
- 60 50. A room and pillar mining machine including a motor having its armature shaft rotatable on an axis extending longitudinally of the machine, a cutter chain driving sprocket rotatable upon a vertical axis, driving means therefor including a gear rotatable coaxially therewith, driving connections between said gear and said armature shaft, and means driven by said motor for feeding and guiding said machine bodily towards and laterally along a mine face during cutting including horizontally journaled feed operating means, and actuating means therefor including a plurality of worms, one of said worms being coaxial with said gear, and friction clutch means between said worms and said feed operating means.
- 55 51. A room and pillar mining machine including a motor having its armature shaft rotatable on an axis extending longitudinally of the machine, a cutter chain driving sprocket rotatable upon a vertical axis, driving means therefor including a gear rotatable coaxially therewith, driving connections between said gear and said armature shaft, and means driven by said motor for feeding and guiding said machine bodily towards and laterally along a mine face during cutting in-

cluding horizontally journaled feed operating means and actuating means therefor including a plurality of worms, one of said worms being coaxial with said gear, said worms being disposed above the plane of said gear, and friction clutch means between said worms and said feed operating means.

52. A room and pillar mining machine including a motor having its armature shaft rotating on an axis extending longitudinally of the machine, a vertical shaft arranged to the rear of said armature shaft and carrying a gear thereon, driving connections between said gear and said armature shaft, a cutter chain driving sprocket coaxial with said gear, means for positively connecting said sprocket and gear; a laterally projecting truck driving member, driving connections between said gear and said truck driving member, and means also driven by said motor for feeding and guiding the machine bodily toward and laterally along a mine face during cutting including horizontally journaled feed operating means and actuating means therefor including a plurality of worms rotatable on vertical axes.

53. A room and pillar mining machine including a motor having its armature shaft rotating on an axis extending longitudinally of the machine, a vertical shaft arranged to the rear of said armature shaft and carrying a gear thereon, driving connections between said gear and said armature shaft, a cutter chain driving sprocket coaxial with said gear, means for positively connecting said sprocket and gear, a laterally projecting truck driving member, driving connections between said gear and said truck driving member, and means also driven by said motor for feeding and guiding the machine bodily toward and laterally along a mine face during cutting including horizontally journaled feed operating means and actuating means therefor including a plurality of worms rotatable on vertical axes one of which is coaxial with said gear.

54. A room and pillar mining machine including a motor having its armature shaft rotating on an axis extending longitudinally of the machine, a vertical shaft arranged to the rear of said armature shaft and carrying a gear thereon, driving connections between said gear and said armature shaft, a cutter chain driving sprocket coaxial with said gear, means for positively connecting said sprocket and gear, a laterally projecting truck driving member, driving connections between said gear and said truck driving member, and means also driven by said motor for feeding and guiding the machine bodily toward and laterally along a mine face during cutting including horizontally journaled feed operating means and actuating means therefor including a plurality of worms rotatable on vertical axes, and fric-

tional clutch means between said worms and said feed operating means.

55. A room and pillar mining machine including a motor having its armature shaft rotating on an axis extending longitudinally of the machine, a vertical shaft arranged to the rear of said armature shaft and carrying a gear thereon, driving connections between said gear and said armature shaft, a cutter chain driving sprocket coaxial with said gear, means for pivotally connecting said sprocket and gear, a laterally projecting truck driving member, driving connections between said gear and said truck driving member, and means also driven by said motor for feeding and guiding the machine bodily toward and laterally along a mine face during cutting including horizontally journaled feed operating means and actuating means therefor including a plurality of worms rotatable on vertical axes one of which is coaxial with said gear, and frictional clutch means between said worms and said feed operating means.

56. In a room and pillar mining machine, a feed operating member adapted to cooperate with a flexible feeding member in effecting transverse feeding, and actuating means therefor including three driving trains arranged in parallel, and controlling means therefor permitting but one train to operate at a given time.

57. In a room and pillar mining machine, a feed operating member adapted to cooperate with a flexible feeding member in effecting transverse feeding, and actuating means therefor including three driving trains arranged in parallel, and controlling means therefor permitting but one train to operate at a given time, one of said trains driving said feed operating member at a cutting speed, another of said trains driving said feed operating member at a machine moving speed, and said third train driving said feed operating member at a speed different from each of said first mentioned speeds.

58. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said feed operating member, means whereby each of said members may be driven by either of said worm wheels, and means for effecting

otation of said worm wheels at different speeds including worms engaging respectively therewith.

59. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said feed operating member, means whereby each of said members may be driven by either of said worm wheels, and means for effecting rotation of said worm wheels at different speeds including worms engaging respectively therewith.

60. In a mining apparatus, in combination, a feed operating member adapted to cooperate directly with flexible feeding means, a truck driving member rotatable on an axis parallel to a line parallel to the axis of rotation of said feed operating member, and actuating means for said members including a plurality of worm wheels coaxial with said feed operating member, and means for effecting rotation of said worm wheels at different speeds including worms engaging respectively therewith and rotating on vertical axes.

61. In a mining apparatus, in combination, a feed operating member adapted to cooperate directly with flexible feeding means, a truck driving member rotatable on an axis parallel to a line parallel to the axis of rotation of said feed operating member, and actuating means for said members including a plurality of worm wheels coaxial with said feed operating member, and means for effecting rotation of said worm wheels at different speeds including worms engaging respectively therewith and rotating on vertical axes at the same side of the axis of rotation of said feed operating member.

62. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis

parallel to a line parallel to the axis of rotation of said feed operating member, and actuating means for said members including a plurality of worm wheels coaxial with said truck driving member, means whereby each of said members may be driven by either of said worm wheels, and means for effecting rotation of said worm wheels at different speeds including worms engaging respectively therewith.

63. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said truck driving member, means whereby each of said members may be driven by either of said worm wheels, and means for effecting rotation of said worm wheels at different speeds including worms engaging respectively therewith and rotating on parallel axes.

64. In a mining apparatus, in combination, a feed operating member adapted to cooperate directly with flexible feeding means, a truck driving member rotatable on an axis parallel to a line parallel to the axis of rotation of said feed operating member, and actuating means for said members including a plurality of worm wheels coaxial with said truck driving member, and means for effecting rotation of said worm wheels at different speeds including worms engaging respectively therewith and rotating on vertical axes.

65. In a mining apparatus, in combination, a feed operating member adapted to cooperate directly with flexible feeding means, a truck driving member rotatable on an axis parallel to a line parallel to the axis of rotation of said feed operating member, and actuating means for said members including a plurality of worm wheels coaxial with said truck driving member, means whereby each of said members may be driven by either of said worm wheels, and means for effecting rotation of said worm wheels at different speeds including worms engaging respectively therewith and rotating on vertical axes at the same side of the axis of rotation of said truck driving member.

66. In a mining machine of the character which performs its normal cutting opera-

14. **70** tions while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member coaxial therewith, and actuating means for said members including a plurality of worm wheels coaxial therewith, means whereby each of said members may be driven by 10 either of said worm wheels, and means for effecting rotation of said worm wheels at different speeds including worms engaging respectively therewith.
15. **75** 20 In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member coaxial therewith, and actuating means for said members including a plurality of worm wheels coaxial therewith, means whereby each of said members may be driven by 25 either of said worm wheels, and means for effecting rotation of said worm wheels at different speeds including worms engaging respectively therewith.
16. **80** 30 In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member coaxial therewith, and actuating means for said members including a plurality of worm wheels coaxial therewith, means whereby each of said members may be driven by 35 either of said worm wheels, and means for effecting rotation of said worm wheels at different speeds including worms engaging respectively therewith and rotating on parallel axes.
17. **85** 40 In a mining apparatus, in combination, a feed operating member adapted to cooperate directly with flexible feeding means, a truck driving member coaxial therewith, and actuating means for said members including a plurality of worm wheels coaxial therewith, and means for effecting rotation of said worm wheels at different speeds including worms engaging respectively therewith and rotating on vertical axes.
18. **90** 45 In a mining apparatus, in combination, a feed operating member adapted to cooperate directly with flexible feeding means, a truck driving member coaxial therewith, and actuating means for said members including a plurality of worm wheels coaxial therewith, and means for effecting rotation of said worm wheels at different speeds including worms engaging respectively therewith and rotating on vertical axes.
19. **95** 50 In a mining apparatus, in combination, a feed operating member adapted to cooperate directly with flexible feeding means, a truck driving member coaxial therewith, and actuating means for said members including a plurality of worm wheels coaxial therewith, and means for effecting rotation of said worm wheels at different speeds including worms engaging respectively therewith and rotating on vertical axes.
20. **100** 55 In a mining apparatus, in combination, a feed operating member adapted to cooperate directly with flexible feeding means, a truck driving member coaxial therewith, and actuating means for said members including a plurality of worm wheels coaxial therewith, and means for effecting rotation of said worm wheels at different speeds including worms engaging respectively therewith and rotating on vertical axes.
21. **105** 60 In a mining apparatus, in combination, a feed operating member adapted to cooperate directly with flexible feeding means, a truck driving member coaxial therewith, and actuating means for said members including a plurality of worm wheels coaxial therewith, and means for effecting rotation of said worm wheels at different speeds including worms engaging respectively therewith and rotating on vertical axes.
22. **110** 65 In a mining apparatus, a feed operating member adapted to cooperate directly with flexible feeding means, a truck driving member, said members rotating on axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith and rotating on vertical axes.
23. **115** 70 In a mining apparatus, a feed operating member adapted to cooperate directly with flexible feeding means, a truck driving member, said members rotating on axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith and rotating on vertical axes.
24. **120** 75 In a mining apparatus of the type which includes a frame slidable on a mine bottom during cutting, a motor and cutting mechanism driven by the motor and including a cutter carrying cutter bar disposed longitudinally of said machine throughout the 125
25. **130** 80

- sumping and lateral cutting operations and wherein said bar is summed into a working face and thereafter fed laterally along such a face with the cutting mechanism operating in the same direction as during the sumping operation, a feed operating member adapted to cooperate directly with flexible feeding means to effect such lateral feeding operation of the machine, a truck driving member, said members rotating on axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith and rotating at different speeds in opposite directions on vertical axes.
74. In a mining apparatus, a feed operating member adapted to cooperate directly with flexible feeding means, a truck driving member, said members rotating on axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith and rotating in opposite directions on parallel axes.
75. In a mining apparatus of the type which includes a frame slidable on a mine bottom during cutting, a motor and cutting mechanism driven by the motor and including a cutter carrying cutter bar disposed longitudinally of said machine throughout the sumping and lateral cutting operations and wherein said bar is summed into a working face and thereafter fed laterally along such a face with the cutting mechanism operating in the same direction as during the sumping operation, a feed operating member adapted to cooperate directly with flexible feeding means to effect such lateral feeding operation of the machine, a truck driving member, said members rotating on horizontal axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith.
76. In a mining apparatus, a feed operating member adapted to cooperate directly with flexible feeding means, a truck driving member, said members rotating on axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith and rotating at different speeds in opposite directions.
77. In a mining apparatus of the type which includes a frame slidable on a mine bottom during cutting, a motor and cutting mechanism driven by the motor and including a cutter carrying cutter bar disposed longitudinally of said machine throughout the sumping and lateral cutting operations and wherein said bar is summed into a working face and thereafter fed laterally along such a face with the cutting mechanism operating in the same direction as during the sumping operation, a feed operating member adapted to cooperate directly with flexible feeding means to effect such lateral feeding operation of the machine, a truck driving member, said members rotating on horizontal axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith.
78. In a mining apparatus of the type which includes a frame slidable on a mine bottom during cutting, a motor and cutting mechanism driven by the motor and including a cutter carrying cutter bar disposed longitudinally of said machine throughout the sumping and lateral cutting operations and wherein said bar is summed into a working face and thereafter fed laterally along such a face with the cutting mechanism operating in the same direction as during the sumping operation, a feed operating member adapted to cooperate directly with flexible feeding means to effect such lateral feeding operation of the machine, a truck driving member, said members rotating on horizontal axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith and rotating on parallel axes.
79. In a mining apparatus, a feed operating member adapted to cooperate directly with flexible feeding means, a truck driving member, said members rotating on horizontal axes parallel to the same straight line, and means for driving said feed operating

member at a predetermined speed and said truck driving member at a higher predetermined speed including worm wheels coaxial with each of said members, and means for driving said worm wheels at different speeds including worms meshing respectively therewith and rotating on vertical axes.

80. In a mining apparatus of the type which includes a frame slidable on a mine bottom during cutting, a motor and cutting mechanism driven by the motor and including a cutter carrying cutter bar disposed longitudinally of said machine throughout the sumping and lateral cutting operations and wherein said bar is sumped into a working face and thereafter fed laterally along such a face with the cutting mechanism operating in the same direction as during the sumping operation, a feed operating member adapted to cooperate directly with flexible feeding means to effect such lateral feeding operation of the machine, a truck driving member, said members rotating on horizontal axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith and rotating in opposite directions on parallel axes.

81. In a mining apparatus, a feed operating member adapted to cooperate directly with flexible feeding means, a truck driving member, said members rotating on horizontal axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith and rotating in opposite directions on vertical axes.

82. In a mining apparatus of the type which includes a frame slidable on a mine bottom during cutting, a motor and cutting mechanism driven by the motor and including a cutter carrying cutter bar disposed longitudinally of said machine throughout the sumping and lateral cutting operations and wherein said bar is sumped into a working face and thereafter fed laterally along such a face with the cutting mechanism operating in the same direction as during the sumping operation, a feed operating member adapted to cooperate directly with flexible feeding means to effect such lateral feeding operation of the machine, a truck driving member, said members rotating on horizontal axes parallel to the same straight line, and means for driving said feed oper-

ating member at a predetermined speed and said truck driving member at a higher predetermined speed including worm wheels coaxial with each of said members, and means for driving said worm wheels at different speeds including worms meshing respectively therewith and rotating at different speeds in opposite directions on parallel axes.

83. In a mining apparatus, a feed operating member adapted to cooperate directly with flexible feeding means, a truck driving member, said members rotating on horizontal axes parallel to the same straight line, and means for driving said feed operating member at a predetermined speed and said truck driving member at a higher predetermined speed including worm wheels coaxial with each of said members, and means for driving said worm wheels at different speeds including worms meshing respectively therewith and rotating at different speeds in opposite directions on vertical axes.

84. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said feed operating member, means for effecting rotation of said worm wheels at different speeds including worms engaging respectively therewith, means whereby each of said members may be driven by either of said worm wheels, and clutch means coaxial with said worm wheels selectively engageable to cause the latter to act selectively as driving elements.

85. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said feed operating member,

- means for effecting rotation of said worm wheels at different speeds including worms engaging respectively therewith and rotating on parallel axes, means whereby each of 5 said members may be driven by either of said worm wheels, and clutch means coaxial with said worm wheels selectively engageable to cause the latter to act selectively as driving elements.
- 10 86. In a mining apparatus, in combination, a feed operating member adapted to cooperate directly with flexible feeding means, a truck driving member rotatable on an axis parallel to a line parallel to the axis 15 of rotation of said feed operating member, and actuating means for said members including a plurality of worm wheels coaxial with said truck driving member, and means for effecting rotation of said worm 20 wheels at different speeds including worms engaging respectively therewith and rotating on vertical axes, and clutch means coaxial with said worm wheels selectively engageable to cause the latter to act selectively as driving elements.
- 25 87. In a mining apparatus, in combination, a feed operating member adapted to cooperate directly with flexible feeding means, a truck driving member rotatable on an axis parallel to a line parallel to the axis 30 of rotation of said feed operating member, and actuating means for said members including a plurality of worm wheels coaxial with said feed operating member, means for effecting rotation of said worm wheels at 35 different speeds including worms engaging respectively therewith and rotating on vertical axes at the same side of the axis of rotation of said feed operating member, and clutch means coaxial with said worm wheels 40 selectively engageable to cause the latter to act selectively as driving elements.
88. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said truck driving member, and means for effecting rotation of said worm wheels at different speeds including worms engaging respectively therewith and rotating on vertical axes at the same side of the axis of rotation of said truck driving member, and clutch means coaxial with said worm wheel selectively engageable to cause the latter to act selectively as driving elements.
- 55 90. In a mining apparatus, in combination, a feed operating member adapted to cooperate directly with flexible feeding means, a truck driving member rotatable on an axis parallel to a line parallel to the axis of rotation of said feed operating member, and actuating means for said members including a plurality of worm wheels coaxial with said truck driving member, and means for effecting rotation of said worm wheels at different speeds including worms engaging respectively therewith and rotating on vertical axes, and clutch means coaxial with said worm wheels selectively engageable to cause the latter to act selectively as driving elements.
- 60 91. In a mining apparatus, in combination, a feed operating member adapted to cooperate directly with flexible feeding means, a truck driving member rotatable on an axis parallel to a line parallel to the axis of rotation of said feed operating member, and actuating means for said members including a plurality of worm wheels coaxial with said truck driving member, and means for effecting rotation of said worm wheels at different speeds including worms engaging respectively therewith and rotating on vertical axes at the same side of the axis of rotation of said truck driving member, and clutch means coaxial with said worm wheel selectively engageable to cause the latter to act selectively as driving elements.
- 65 92. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said truck driving member, and means for effecting rotation of said worm wheels at different speeds including worms engaging respectively therewith and rotating on vertical axes, and clutch means coaxial with said worm wheels selectively engageable to cause the latter to act selectively as driving elements.

with flexible feeding means to effect cutting feed upon the mine bottom and movements of the machine relative to and upon a truck, a truck driving member coaxial therewith, and actuating means for said members including a plurality of worm wheels coaxial therewith and means for effecting rotation of said worm wheels at different speeds including worms engaging respectively therewith, and clutch means coaxial with said worm wheels selectively engageable to cause the latter to act selectively as driving elements.

93. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member coaxial therewith, and actuating means for said members including a plurality of worm wheels coaxial therewith and means for effecting rotation of said worm wheels at different speeds including worms engaging respectively therewith and rotating on parallel axes, and clutch means coaxial with said worm wheels selectively engageable to cause the latter to act selectively as driving elements.

94. In a mining apparatus, in combination, a feed operating member adapted to cooperate directly with flexible feeding means, a truck driving member coaxial therewith, and actuating means for said members including a plurality of worm wheels coaxial therewith, and means for effecting rotation of said worm wheels at different speeds including worms engaging respectively therewith and rotating on vertical axes, and clutch means coaxial with said worm wheels selectively engageable to cause the latter to act selectively as driving elements.

95. In a mining apparatus, in combination, a feed operating member adapted to cooperate directly with flexible feeding means, a truck driving member coaxial therewith, and actuating means for said members including a plurality of worm wheels coaxial therewith, and means for effecting rotation of said worm wheels at different speeds including worms engaging respectively therewith and rotating on vertical axes at the same side of the axes of rotation of said members, and clutch means coaxial with said worm wheels selectively engageable to cause the latter to act selectively as driving elements.

96. In a mining machine of the character

which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said feed operating member, means whereby each of said members may be driven by either of said worm wheels, and means for effecting rotation of said worm wheels at different speeds including oppositely rotating worms engaging respectively therewith.

97. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said feed operating member, means whereby each of said members may be driven by either of said worm wheels, and means for effecting rotation of said worm wheels at different speeds including worms engaging respectively therewith and rotating in opposite directions on parallel axes.

98. In a mining apparatus, in combination, a feed operating member adapted to cooperate directly with flexible feeding means, a truck driving member rotatable on an axis parallel to a line parallel to the axis of rotation of said feed operating member, and actuating means for said members including a plurality of worm wheels coaxial with said feed operating member, and means for effecting rotation of said worm wheels at different speeds including worms engaging respectively therewith and rotating in opposite directions on vertical axes.

99. In a mining apparatus, in combination, a feed operating member adapted to cooperate directly with flexible feeding means, a truck driving member rotatable on an axis parallel to a line parallel to the axis of rotation of said feed operating member, and actuating means for said members in-

- cluding a plurality of worm wheels coaxial with said feed operating member, and means for effecting rotation of said worm wheels at different speeds including worms engaging respectively therewith and rotating in opposite directions on vertical axes at the same side of the axis of rotation of said feed operating member.
100. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said truck driving member, means whereby each of said members may be driven by either of said worm wheels, and means for effecting rotation of said worm wheels at different speeds including oppositely rotating worms engaging respectively therewith.
101. In a mining machine of the character which performs its normal cutting operations while sliding upon the mine bottom and is transported from one working place to another upon a truck from which it is dismounted during the normal cutting operations aforesaid, in combination a feed operating member adapted to cooperate directly with flexible feeding means to effect cutting feed upon the mine bottom and movements of the machine relative to and upon a truck, a truck driving member rotatable on an axis parallel to a line parallel to the axis of rotation of said feed operating member, and actuating means for said members including a plurality of worm wheels coaxial with said truck driving member, means whereby each of said members may be driven by either of said worm wheels, and means for effecting rotation of said worm wheels at different speeds including oppositely rotating worms engaging respectively therewith.
102. In a mining apparatus, in combination, a feed operating member adapted to cooperate directly with flexible feeding means, a truck driving member rotatable on an axis parallel to a line parallel to the axis of rotation of said feed operating member, and actuating means for said members including a plurality of worm wheels coaxial with said truck driving member, and means for effecting rotation of said worm wheels at different speeds including worms engag-
- ing respectively therewith and rotating in opposite directions on vertical axes.
103. In a mining apparatus, in combination, a feed operating member adapted to cooperate directly with flexible feeding means, a truck driving member rotatable on an axis parallel to a line parallel to the axis of rotation of said feed operating member, and actuating means for said members including a plurality of worm wheels coaxial with said truck driving member, and means for effecting rotation of said worm wheels at different speeds including worms engaging respectively therewith and rotating in opposite directions on vertical axes at the same side of the axis of rotation of said truck driving member.
104. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member coaxial therewith, and actuating means for said members including a plurality of worm wheels coaxial therewith, means whereby each of said members may be driven by either of said worm wheels, and means for effecting rotation of said worm wheels at different speeds including oppositely rotating worms engaging respectively therewith.
105. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member coaxial therewith, and actuating means for said members including a plurality of worm wheels coaxial therewith, means whereby each of said members may be driven by either of said worm wheels, and means for effecting rotation of said worm wheels at different speeds including worms engag-
106. In a mining apparatus, in combination, a feed operating member adapted to cooperate directly with flexible feeding means, a truck driving member coaxial therewith, and actuating means for said members including a plurality of worm wheels coaxial therewith, and means for ef-

fecting rotation of said worm wheels at different speeds including worms engaging respectively therewith and rotating in opposite directions on vertical axes.

5 107. In a mining apparatus, in combination, a feed operating member adapted to cooperate directly with flexible feeding means, a truck driving member coaxial therewith, and actuating means for said members including a plurality of worm wheels coaxial therewith, and means for effecting rotation of said worm wheels at different speeds including worms engaging respectively therewith and rotating in opposite directions on vertical axes at the same side of the axes of rotation of said members.

15 108. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means and rotating on a horizontal axis, said feed operating member being operative to effect cutting feed and movements of the machine relative to and upon a truck, a truck driving member rotatable on an axis parallel to a line parallel to the axis of rotation of said feed operating member, and actuating means for said members including a plurality of worm wheels coaxial with said feed operating member, means whereby each of said members may be driven by either of said worm wheels, and means for effecting rotation of said worm wheels at different speeds including worms engaging respectively therewith.

20 109. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means and rotating on a horizontal axis, said feed operating member being operative to effect cutting feed and movements of the machine relative to and upon a truck, a truck driving member rotatable on an axis parallel to a line parallel to the axis of rotation of said feed operating member, and actuating means for said members including a plurality of worm wheels coaxial with said feed operating member, means whereby each of said members may be driven by either of said worm wheels, and means for effecting rotation of said worm wheels at different speeds including worms engaging respectively therewith and rotating on parallel axes.

25 110. In a mining apparatus, in combination, a feed operating member adapted to cooperate directly with flexible feeding means and rotating on a horizontal axis, a truck driving member rotatable on an axis parallel to a line parallel to the axis of rotation of said feed operating member, and actuating means for said members including a plurality of worm wheels coaxial with said feed operating member, and means for effecting rotation of said worm wheels at different speeds including worms engaging respectively therewith and rotating on vertical axes.

30 111. In a mining apparatus, in combination, a feed operating member adapted to cooperate directly with flexible feeding means and rotating on a horizontal axis, a truck driving member rotatable on an axis parallel to a line parallel to the axis of rotation of said feed operating member, and actuating means for said members including a plurality of worm wheels coaxial with said feed operating member, and means for effecting rotation of said worm wheels at different speeds including worms engaging respectively therewith and rotating on vertical axes at the same side of the axis of rotation of said feed operating member.

35 112. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means and rotating on a horizontal axis, said feed operating member being operative to effect cutting feed and movements of the machine relative to and upon a truck, a truck driving member rotatable on an axis parallel to a line parallel to the axis of rotation of said feed operating member, and actuating means for said members including a plurality of worm wheels coaxial with said truck driving member, means whereby each of said members may be driven by either of said worm wheels, and means for effecting rotation of said worm wheels at different speeds including worms engaging respectively therewith.

40 113. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means and rotating on a horizontal axis, said feed operating member being operative to effect cutting feed and movements of the machine relative to and upon a truck, a truck driving member

5 rotatable on an axis parallel to a line parallel to the axis of rotation of said feed operating member, and actuating means for said members including a plurality of worm wheels coaxial with said truck driving member, means whereby each of said members may be driven by either of said worm wheels, and means for effecting rotation of said worm wheels at different speeds including worms engaging respectively therewith and rotating on parallel axes.

10 114. In a mining apparatus, in combination, a feed operating member adapted to cooperate directly with flexible feeding means and rotating on a horizontal axis, a truck driving member rotatable on an axis parallel to a line parallel to the axis of rotation of said feed operating member, and actuating means for said members including a plurality of worm wheels coaxial with said truck driving member, and means for effecting rotation of said worm wheel at different speeds including worms engaging respectively therewith and rotating on vertical axes.

15 115. In a mining apparatus, in combination, a feed operating member adapted to cooperate directly with flexible feeding means and rotating on a horizontal axis, a truck driving member rotatable on an axis parallel to a line parallel to the axis of rotation of said feed operating member, and actuating means for said members including a plurality of worm wheels coaxial with said truck driving member, and means for effecting rotation of said worm wheels at different speeds including worms engaging respectively therewith and rotating on vertical axes at the same side of the axis of rotation of said truck driving member.

20 116. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means and rotating on a horizontal axis, said feed operating member being operative to effect cutting feed and movements of the machine relative to and upon a truck, a truck driving member coaxial therewith, and actuating means for said members including a plurality of worm wheels coaxial therewith, means whereby each of said members may be driven by either of said worm wheels, and means for effecting rotation of said worm wheels at different speeds including worms engaging respectively therewith.

25 117. In a mining machine of the character which performs its normal cutting operations while sliding upon the mine bottom

30 and is transported from one working place to another upon a truck from which it is dismounted during the normal cutting operations aforesaid, in combination, a feed operating member adapted to cooperate directly with flexible feeding means and rotating on a horizontal axis, said feed operating member being operative to effect cutting feed and movements of the machine relative to and upon a truck, a truck driving member coaxial therewith, and actuating means for said members including a plurality of worm wheels coaxial therewith, means whereby each of said members may be driven by either of said worm wheels, and means for effecting rotation of said worm wheels at different speeds including worms engaging respectively therewith and rotating on parallel axes.

35 118. In a mining apparatus, in combination, a feed operating member adapted to cooperate directly with flexible feeding means and rotating on a horizontal axis, a truck driving member coaxial therewith, and actuating means for said members including a plurality of worm wheels coaxial therewith, and means for effecting rotation of said worm wheels at different speeds including worms engaging respectively therewith and rotating on vertical axes.

40 119. In a mining apparatus, in combination, a feed operating member adapted to cooperate directly with flexible feeding means and rotating on a horizontal axis, a truck driving member coaxial therewith, and actuating means for said members including a plurality of worm wheels coaxial therewith, and means for effecting rotation of said worm wheels at different speeds including worms engaging respectively therewith and rotating on vertical axes at the same side of the axes of rotation of said members.

45 120. In a mining apparatus of the type which includes a frame slidable on a mine bottom during cutting, a motor having a horizontal axis of rotation and cutting mechanism driven by the motor and including a cutter carrying cutter bar disposed longitudinally of said machine throughout the sumping and lateral cutting operations and wherein said bar is sumped into a working face and thereafter fed laterally along such a face with the cutting mechanism operating in the same direction as during the sumping operation, a feed operating member having a horizontal axis of rotation and adapted to cooperate directly with flexible feeding means to effect such lateral feeding operation of the machine, and driving connections between the motor and feed operating member including a pinion on said motor, a gear driven thereby, a pinion rotating with said gear, a second gear rotated by said second pinion, a worm rotating with said second

gear, and a worm wheel coaxial with said feed operating member and driven by said worm.

121. In a mining apparatus of the type which includes a frame slidable on a mine bottom during cutting, a motor having a horizontal axis of rotation extending longitudinally of said apparatus and cutting mechanism driven by the motor and including a cutter carrying cutter bar disposed longitudinally of said machine throughout the sumping and lateral cutting operations and wherein said bar is sumped into a working face and thereafter fed laterally along such a face with the cutting mechanism operating in the same direction as during the sumping operation, a feed operating member having horizontal axis of rotation and adapted to cooperate directly with flexible feeding means to effect such lateral feeding operation of the machine, and driving connections between the motor and feed operating member including a pinion on said motor, a gear driven thereby, a pinion rotating with said gear, a second gear rotated by said second pinion, a worm rotating with said second gear, and a worm wheel coaxial with said feed operating member and driven by said worm.

122. In a mining apparatus of the type which includes a frame slidable on a mine bottom during cutting, a motor having a horizontal axis of rotation and cutting mechanism driven by the motor and including a cutter carrying cutter bar disposed longitudinally of said machine throughout the sumping and lateral cutting operations and wherein said bar is sumped into a working face and thereafter fed laterally along such a face with the cutting mechanism operating in the same direction as during the sumping operation, a feed operating member having a horizontal axis of rotation and adapted to cooperate directly with flexible feeding means to effect such lateral feeding operation of the machine, and plural speed driving connections between said motor and feed operating member including a pinion on said motor, a gear driven thereby, a second pinion rotating with said gear, a second gear driven by said second pinion, a third pinion rotating with said second gear, a third gear driven by said third pinion, worms respectively coaxial with said second and third gears, and worm wheels driven by said worms and coaxial with said feed operating member and selectively adapted to drive the same.

123. In a mining machine of the character which performs its normal cutting operations while sliding upon the mine bottom and is transported from one working place to another upon a truck from which it is dismounted during the normal cutting operations aforesaid, a motor having a hori-

zontal axis of rotation extending longitudinally of said apparatus, a feed operating member having a horizontal axis of rotation and adapted to cooperate directly with flexible feeding means, said feed operating member being operative to effect cutting feed and movements of the machine relative to and upon a truck, and plural speed driving connections between said motor and feed operating member including a pinion on said motor, a gear driven thereby, a second pinion rotating with said gear, a second gear driven by said second pinion, a third pinion rotating with said second gear, a third gear driven by said third pinion, worms respectively coaxial with said second and third gears, and worm wheels driven by said worms and coaxial with said feed operating member and selectively adapted to drive the same.

124. In a mining apparatus, a machine frame slidable on its bottom over a mine bottom during cutting and having projecting therefrom at one end thereof cutting mechanism, said frame also carrying a motor driving said cutting mechanism and having a horizontal axis of rotation, and at the end of said frame opposite that from which said cutting mechanism projects a truck driving member having a horizontal axis of rotation and adapted to cooperate directly with flexible power transmission connections, and driving connections between the motor and truck driving member including a pinion on said motor, a gear driven thereby, a pinion rotating with said gear, a second gear rotated by said second pinion, a worm rotating with said second gear, and a worm wheel coaxial with said truck driving member and driven by said worm.

125. In a mining apparatus, a machine frame slidable on its bottom over a mine bottom during cutting and having projecting therefrom at one end thereof cutting mechanism, said frame also carrying a motor driving said cutting mechanism and having a horizontal axis of rotation extending longitudinally of said frame, and at the end of said frame opposite that from which said cutting mechanism projects a truck driving member having a horizontal axis of rotation and adapted to cooperate directly with flexible power transmission connections, and driving connections between the motor and truck driving member including a pinion on said motor, a gear driven thereby, a pinion rotating with said gear, a second gear rotated by said second pinion, a worm rotating with said second gear, and a worm wheel coaxial with said truck driving member and driven by said worm.

126. In a mining apparatus of the character which performs its normal cutting operations while sliding on the mine bottom and is transported from one working place

- to another upon a truck from which it is dismounted during the normal cutting operations aforesaid, a machine frame slidable upon the mine bottom and enclosing a 5 motor having a horizontal axis of rotation, a truck driving member having a horizontal axis of rotation and adapted to cooperate directly with flexible power transmission means to effect truck propulsion, and plural 10 speed driving connections between said motor and truck driving member including a pinion on said motor, a gear driven thereby, a second pinion rotating with said gear, a second gear driven by said second pinion, 15 a third pinion rotating with said second gear, a third gear driven by said third pinion, worms respectively coaxial with said second and third gears, and worm wheels driven by said worms and coaxial 20 with said truck driving member and selectively adapted to drive the same.
127. In a mining apparatus of the character which performs its normal cutting operations while sliding on the mine bottom 25 and is transported from one working place to another upon a truck from which it is dismounted during the normal cutting operations aforesaid, a machine frame slidable upon the mine bottom and enclosing a 30 motor having a horizontal axis of rotation extending longitudinally of said frame, a truck driving member having a horizontal axis of rotation and adapted to cooperate directly with flexible power transmission 35 means to effect truck propulsion, and plural speed driving connections between said motor and truck driving member including a pinion on said motor, a gear driven thereby, a second pinion rotating with said gear, a second gear driven by said second pinion, 40 a third pinion rotating with said second gear, a third gear driven by said third pinion, worms respectively coaxial with said second and third gears, and worm wheels 45 driven by said worms and coaxial with said truck driving member and selectively adapted to drive the same.
128. In a mining apparatus of the character which performs its normal cutting operations while sliding on the mine bottom 50 and is transported from one working place to another upon a truck from which it is dismounted during the normal cutting operations aforesaid, a motor having a horizontal axis of rotation, a feed operating member having a horizontal axis of rotation and adapted to cooperate directly with flexible feeding means to effect cutting feed and 55 movements of said machine relative to and upon a truck, a truck driving member coaxial therewith, and driving connections between the motor and feed operating member including a pinion on said motor, a gear driven thereby, a pinion rotating with said gear, a second gear 60 driven by said second pinion, a third pinion rotating with said second gear, a third gear driven by said third pinion, worms respectively coaxial with said second and third gears, worm wheels driven by said worms and coaxial with said feed operating and truck driving members and selectively adapted to drive the same and means whereby each of said members may be driven by said worm wheel.
129. In a mining apparatus of the character which performs its normal cutting operations while sliding on the mine bottom and is transported from one working place to another upon a truck from which it is dismounted during the normal cutting operations aforesaid, a motor having a horizontal axis of rotation extending longitudinally of 75 said apparatus, a feed operating member having a horizontal axis of rotation and adapted to cooperate directly with flexible feeding means to effect cutting feed and movements of said machine relative to and upon a truck, a truck driving member coaxial 80 therewith, and driving connections between the motor and feed operating member including a pinion on said motor, a gear driven thereby, a pinion rotating with said gear, a second gear rotated by said second pinion, 85 a worm rotating with said second gear, a worm wheel coaxial with said feed operating and truck driving members and driven by said worm, and means whereby each of 90 said members may be driven by said worm 95 wheel.
130. In a mining apparatus of the character which performs its normal cutting operations while sliding on the mine bottom and is transported from one working place to another upon a truck from which it is dismounted during the normal cutting operations aforesaid, a motor having a horizontal axis of rotation, a feed operating member having a horizontal axis of rotation and adapted to cooperate directly with flexible feeding means to effect cutting feed and movements of said machine relative to and upon a truck, a truck driving member coaxial therewith, and plural speed driving 100 connections between said motor and feed operating member including a pinion on said motor, a gear driven thereby, a second pinion rotating with said gear, a second gear driven by said second pinion, a third pinion 105 rotating with said second gear, a third gear driven by said third pinion, worms respectively coaxial with said second and third gears, worm wheels driven by said worms and coaxial with said feed operating and truck driving members and selectively adapted to drive the same and means whereby each of said members may be driven by said worm 110 wheel.
131. In a mining apparatus of the character which performs its normal cutting operations while sliding on the mine bottom and is transported from one working place to another upon a truck from which it is dismounted during the normal cutting opera- 115 120 125 130

tions aforesaid, a motor having a horizontal axis of rotation extending longitudinally of said apparatus, a feed operating member having a horizontal axis of rotation and adapted to cooperate directly with flexible feeding means to effect cutting feed and movements of said machine relative to and upon a truck, a truck driving member coaxial with said feed operating member, and plural speed driving connections between said motor and feed operating member including a pinion on said motor, a gear driven thereby, a second pinion rotating with said gear, a second gear driven by said second pinion, a third pinion rotating with said second gear, a third gear driven by said third pinion, worms respectively coaxial with said second and third gears, worm wheels driven by said worms and coaxial with said feed operating and truck driving members and selectively adapted to drive the same and means whereby each of said members may be driven by said worm wheels.

132. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member coaxial with said feed operating member, and actuating means for said members including a plurality of worm wheels rotating on axes parallel to a line parallel to the axis of rotation of said feed operating and truck driving members, means whereby each of said members may be driven by either of said worm wheels, and means for effecting rotation of said worm wheels at different speeds including worms engaging respectively therewith.

133. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member coaxial with said feed operating member, and actuating means for said members including a plurality of worm wheels rotating on axes parallel to a line parallel to the axis of rotation of said feed, operating and truck driving members, means whereby each of said members may be driven by either of said worm wheels, and means for effecting rotation of said worm

wheels at different speeds including worms engaging respectively therewith and rotating on parallel axes.

134. In a mining apparatus, in combination, a feed operating member adapted to cooperate directly with flexible feeding means, a truck driving member coaxial with said feed operating member, and actuating means for said members including a plurality of worm wheels rotating on axes parallel to a line parallel to the axis of rotation of said feed operating and truck driving members, and means for effecting rotation of said worm wheels at different speeds including worms engaging respectively therewith and rotating on vertical axes.

135. In a mining apparatus, in combination, a feed operating member adapted to cooperate directly with flexible feeding means, a truck driving member coaxial with said feed operating member, and actuating means for said members including a plurality of worm wheels rotating on axes parallel to a line parallel to the axis of rotation of said feed operating and truck driving members, and means for effecting rotation of said worm wheels at different speeds including worms engaging respectively therewith and rotating on vertical axes at the same side of the axis of rotation of said feed operating member.

136. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means to effect cutting feed upon the mine bottom and movements of the machine relative to and upon a truck, a truck driving member coaxial with said feed operating member, and actuating means for said members including a plurality of worm wheels rotating on axes parallel to a line parallel to the axis of rotation of said feed operating and truck driving members, and means for effecting rotation of said worm wheels at different speeds including worms engaging respectively therewith and a motor for actuating said worms arranged at the opposite side therefrom with respect to said feed operating and truck driving members.

137. In a mining machine of the character which performs its normal cutting operations while sliding upon the mine bottom and is transported from one working place to another upon a truck from which it is dismounted during the normal cutting operation aforesaid, in combination, a feed operating member adapted to cooperate directly with flexible feeding means and rotatable on a horizontal axis, said feed oper-

- ating member being operative to effect cutting feed and movements of the machine relative to and upon a truck, a truck driving member coaxial with said feed operating member, and actuating means for said members including a plurality of worm wheels rotating on axes parallel to a line parallel to the axis of rotation of said feed operating and truck driving members, means whereby each of said members may be driven by either of said worm wheels, and means for effecting rotation of said worm wheels at different speeds including worms engaging respectively therewith.
138. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means and rotatable on a horizontal axis, said feed operating member being operative to effect cutting feed and movements of the machine relative to and upon a truck, a truck driving member coaxial with said feed operating member, and actuating means for said members including a plurality of worm wheels rotating on axes parallel to a line parallel to the axes of rotation of said feed operating and truck driving members, and means for effecting rotation of said worm wheels at different speeds including worms engaging respectively therewith, and a motor for actuating said worms arranged at the opposite side therefrom with respect to said feed operating and truck driving members.
139. In a mining apparatus, in combination, a feed operating member adapted to cooperate directly with flexible feeding means and rotatable on a horizontal axis, a truck driving member coaxial with said feed operating member, and actuating means for said members including a plurality of worm wheels rotating on axes parallel to a line parallel to the axis of rotation of said feed operating and truck driving members, and means for effecting rotation of said worm wheels at different speeds including worms engaging respectively therewith and rotating on vertical axes.
140. In a mining apparatus, in combination, a feed operating member adapted to cooperate directly with flexible feeding means and rotatable on a horizontal axis, a truck driving member coaxial with said feed operating member, and actuating means for said members including a plurality of worm wheels rotating on axes parallel to a line parallel to the axis of rotation of said feed operating and truck driving members, and means for effecting rotation of said worm wheels at different speeds including worms
- worms engaging respectively therewith and rotating on vertical axes at the same side of the axis of rotation of said feed operating member.
141. In a mining machine of the character which performs its normal cutting operations while sliding upon the mine bottom and is transported from one working place to another upon a truck from which it is dismounted during the normal cutting operations aforesaid, in combination, a feed operating member adapted to cooperate directly with flexible feeding means and rotatable on a horizontal axis, said feed operating member being operative to effect cutting feed and movements of the machine relative to and upon a truck, a truck driving member coaxial with said feed operating member, and actuating means for said members including a plurality of worm wheels rotating on axes parallel to a line parallel to the axes of rotation of said feed operating and truck driving members, and means for effecting rotation of said worm wheels at different speeds including worms engaging respectively therewith.
142. In a mining machine of the character which performs its normal cutting operations while sliding upon the mine bottom and is transported from one working place to another upon a truck from which it is dismounted during the normal cutting operations aforesaid, in combination, a frame, and feed operating and truck driving means thereon including a feed operating member adapted to cooperate directly with flexible feeding means, said feed operating member being operative to effect cutting feed and movements of the machine relative to and upon a truck, a truck driving member rotatable coaxially therewith, said members being disposed adjacent one end of said frame, a motor adjacent the opposite end of said frame, and driving connections between said feed operating and truck driving members and said motor including a plurality of worms intermediate said motor and said feed operating and truck driving members, and means whereby each of said members may be driven by either of said worms.
143. In a mining apparatus, in combination, a frame, and feed operating and truck driving means thereon including a feed operating member adapted to cooperate directly with flexible feeding means, a truck driving member rotatable coaxially therewith, said members being disposed adjacent one end of said frame, a motor adjacent the opposite end of said frame, and driving connections between said feed operating and truck driving members and said motor including a plurality of worms rotating on

vertical axes intermediate said motor and said feed operating and truck driving members.

144. In a mining machine of the character which performs its normal cutting operations while sliding upon the mine bottom and is transported from one working place to another upon a truck from which it is dismounted during the normal cutting operations aforesaid, in combination, a frame, and feed operating and truck driving means thereon including a feed operating member adapted to cooperate directly with flexible feeding means, said feed operating member being operative to effect cutting feed and movements of the machine relative to and upon a truck, a truck driving member rotatable coaxially therewith, said members being disposed adjacent one end of said frame, a motor adjacent the opposite end of said frame, and driving connections between said feed operating and truck driving members and said motor including a plurality of worms rotating in opposite directions and disposed intermediate said motor and said feed operating and truck driving members, and means whereby each of said members may be driven by either of said worms.
145. In a mining apparatus, in combination, a frame, and feed operating and truck driving means thereon including a feed operating member adapted to cooperate directly with flexible feeding means, a truck driving member rotatable coaxially therewith, said members being disposed adjacent one end of said frame, a motor adjacent the opposite end of said frame, and driving connections between said feed operating and truck driving members and said motor including a plurality of worms rotating on vertical axes in opposite directions and disposed intermediate said motor and said feed operating and truck driving members.
146. In a mining machine of the character which performs its normal cutting operations while sliding upon the mine bottom and is transported from one working place

to another upon a truck from which it is dismounted during the normal cutting operations aforesaid, in combination, a frame, and feed operating and truck driving means thereon including a feed operating member adapted to cooperate directly with flexible feeding means, said feed operating member being operative to effect cutting feed and movements of the machine relative to and upon a truck, a truck driving member rotatable coaxially therewith, said members being disposed adjacent one end of said frame, a motor adjacent the opposite end of said frame, and driving connections between said feed operating and truck driving members and said motor including a plurality of worms rotating at different speeds and disposed intermediate said motor and said feed operating and truck driving members, and means whereby each of said members may be driven by either of said worms.

147. In a mining machine of the character which performs its normal cutting operations while sliding upon the mine bottom and is transported from one working place to another upon a truck from which it is dismounted during the normal cutting operations aforesaid, in combination, a frame, and feed operating and truck driving means thereon including a feed operating member adapted to cooperate directly with flexible feeding means, said feed operating member being operative to effect cutting feed and movements of the machine relative to and upon a truck, a truck driving member rotatable coaxially therewith, said members being disposed adjacent one end of said frame, a motor adjacent the opposite end of said frame, and driving connections between said feed operating and truck driving members and said motor including a plurality of worms rotating in opposite directions at different speeds and disposed intermediate said motor and said feed operating and truck driving members, and means whereby each of said members may be driven by either of said worms.

In testimony whereof I affix my signature.
MORRIS P. HOLMES.
